US00D786326S

(12) **United States Design Patent** (10) Patent No.: **US D786,326 S**
Jeong (45) Date of Patent: ** May 9, 2017

(54) **CUTTING INSERT**

- (71) Applicant: **TaeguTec Ltd.**, Daegu (KR)
(72) Inventor: **Chang Won Jeong**, Daegu (KR)
(73) Assignee: **TaeguTec Ltd.**, Daegu (KR)
(**) Term: **15 Years**
(21) Appl. No.: **29/546,453**
(22) Filed: **Nov. 23, 2015**
(51) LOC (10) Cl. **15-09**
(52) U.S. Cl.
USPC **D15/139**
(58) **Field of Classification Search**
USPC D8/20, 70; D15/126, 131, 138, 139, 140
See application file for complete search history.

Primary Examiner — Patricia Palasik

(74) Attorney, Agent, or Firm — Hamre, Schumann, Mueller & Larson, P.C.

(57) **CLAIM**

The ornamental design for a cutting insert, as shown and described.

DESCRIPTION

FIG. 1 is a perspective view of a cutting insert showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings depict unclaimed environmental subject matter.
